PARACHUTE HARNESS

John Raymond Cuthbert Quilter,
Woking, EnglandApplication October 19, 1945, Serial No. 623,328
In Great Britain September 27, 1944Section 1, Public Law 690, August 8, 1946
Patent expires September 27, 1964

10 Claims. (Cl. 244—151)

1

This invention relates to parachute harness for aviators.

The invention has for its main object to provide an improved harness of the type including a seat loop in which the aviator sits as in a sling, but comprising two front lift webs or like parachute connections each carrying one half of the entire load, these connections being individually locked to the respective extremities of the seat loop.

Another object of the invention is to provide a parachute harness of this kind in which the locking of the lift webs or like parachute connections to the extremities of the seat loop is effected by separate devices adapted for individual locking and for simultaneous release.

A further object of the invention is to provide a harness comprising front lift webs or like parachute connections carrying the entire load, wherein the release of the harness is effected by manipulation of a single controlling means; the operation of this controlling means frees the aviator completely from the harness, which can open out and slip off the body as soon as said controlling means is operated.

Other objects and advantages of the invention will hereinafter appear from the following description of a preferred embodiment, reference being had to the accompanying drawings, in which—

Fig. 1 shows a parachute harness provided with a central control box and two separate quick-release devices at the lower ends of the front lift webs, the harness affording release at four points simultaneously.

Fig. 2 is a plan of the central control box, on a larger scale, showing the connections thereto.

Fig. 3 is a partial plan showing one of the side connectors pulling out of the central control box upon release.

Fig. 4 is a front view of one of the leg release devices, also on a larger scale with the cover plate partly removed.

Figs. 5 and 6 are sectional views of the leg release device, in the engaged and the disengaged positions respectively.

Referring first to Fig. 1, the harness comprises two lift webs 10 which hang in front of the wearer's body and carry the entire load, these webs passing through buckles 11 over the shoulders and continuing to join the lift straps (not shown) in the parachute pack, which may be carried by a base frame 9 worn upon the back or otherwise. The lower ends of the lift webs 10 are connected to two quick-release devices 12 detachably en-

2

gaged with lugs 13 connected to the ends of a leg strap 14 which is adapted to pass down outside the wearer's legs and across beneath them, so as to form a seat loop in which he sits as in a sling; both ends of this leg strap or seat loop are adjustably attached to their lugs 13 by means of frictional buckles 15 upon connectors 16 having the lugs 13 secured to their other ends, so that the leg strap 14 can be tightened evenly to ensure comfort in wear. Leg loops 17, which may also be provided with adjustable buckles 18 or other tensioning means, are secured to two points near the center of the leg strap 14, these loops being carried up between the wearer's legs and engaged around the leg strap connectors 16 before the latter are engaged with the leg-release devices 12. The main lift webs 10 are provided with side braces 19 extending between them and partly across the wearer's chest; each of these side braces is fitted with means for detachable engagement with a central control box 20 mounted upon a waist band 21 attached to the harness. This waist band is made of wide webbing material, fitted at one end with the control box 20, the band being of sufficient length to wrap around one side (preferably the left side) and partly across the back of the wearer's body, being attached as by stitching to a pair of back braces 22 running diagonally from the shoulder buckles 11 on the main lift webs 10 downwards to opposite sides of the leg strap or seat loop 14; the waist band is interrupted on one side (viz., the right side) so that it can open out and slip off the wearer's body as soon as the harness straps are released by manipulation of the controlling means.

The central control box 20 comprises a body having two opposite slots 23 for the admission of lugs 24 carried by the side braces 19, the lugs being engaged by spring-loaded plungers or locking studs 25 of the known kind, the release of which is obtained by turning and then pressing a rotatable knob 26 on the front of the box. Each lug 24 is integral with a sliding plunger 27 mounted in a guide socket 28 connected to the respective side brace 19; a knurled sleeve 29, slidable along the exterior of the socket, is secured by a transverse pin 30 to the plunger inside the socket, which is slotted longitudinally to allow a limited movement of the pin. A flexible wire 31 attached to the plunger runs through a flexible casing 32 from the end of the socket down to the top of the quick release device 12 at the lower end of the lift web on this side of the harness; the wire is tensioned by a spring or springs inside the quick release device, as hereinafter described.

When engaging the side braces with the control box, the knurled sleeves 29 are gripped and slid along the guide sockets 28 so that the lugs 24 project from the sockets and can be pushed through the slotted walls of the box into locking engagement with the spring-loaded studs therein; in this position, the springs inside the quick-release devices will be held under tension. The sleeves 29 bear upon projections 33 on the sockets holding the latter firmly against the walls of the box, while any pull on the side braces is taken by the projections 33 and resisted by the sleeves 29 which are locked by the engagement of the lugs 24 inside the box, so that such pull on the side braces does not affect the spring tension on the wires 31.

Upon release of the central control by the customary rotation and pressing of the knob 26, the locking studs 25 disengage the lugs 24, the plungers 27 being pulled back by the wires 31 under spring tension; as seen in Fig. 3, the knurled sleeve 29 slides back along the exterior of the guide socket to the limit of its movement, and the side brace 19 is released from the control box.

Each of the quick-release devices 12 at the lower ends of the main lift webs 10 is simultaneously freed so that the lugs 13 connected to the leg strap or seat loop are disengaged in order to release the latter from the lift webs, with consequential release of the leg loops 17. As seen in Figs. 4 to 6, the quick-release device 12 comprises a body 25 formed with a slotted base-plate or attachment 34 for the lift web 10, the bottom wall of the body being slotted at 35 to admit the lug 13 connected to the leg strap or seat loop; upon the body there is mounted a cover plate 36 having a bottom flange 37 and two side flanges 38. These flanges 38 carry attached pivots 39 engaged in the walls of the body, so that the cover plate can rock upon the axis of the pivots; above this axis, the side flanges are cranked inwards to form ears 40 parallel to the back of the cover plate. Inside the cover plate, there is secured an L-shaped block 41, of which one edge is fixed to the front of the cover plate by screws 42 and the other edge rests upon the bottom flange 37 of the cover plate; the block 41 forms a guide for the locking stud 43 which has the usual bevelled extremity 44 projecting normally into the slot 35 and is loaded by a spring 45, as seen in Fig. 5.

The flexible wire 31 on each side and its casing 32 extend to the top of the corresponding leg-release device 12, the wire entering through a screw nipple 46 which provides an adjustable abutment for the casing; the extremity of the wire is attached to a shoe 47 which can slide between the ears 40 of the cover and the flat surface 48 inside the body of the device. This shoe is provided with springs 49 anchored to the bottom wall at 50, the tension of these springs being transmitted along the wire 31 to the plunger 27 of the side brace lug 24; the springs 49 therefore remain tensioned, with the shoe 47 in the raised position of Fig. 5, so long as the lugs 24 are engaged in the central control box 20.

Release of the lugs 24 by manipulation of the rotatable knob 26, as described above, will allow the springs 49 of both leg-release devices to draw their shoes 47 down the surfaces 48 into alignment with the axes of the respective pivots 39, in which position the shoes are below the ears 40 of the cover plates; the pull of the leg strap or seat loop lugs 14 upon the studs 43 will therefore rock the cover plates 36 and move the studs 43 clear of the lugs 13, which thus escape as shown in Fig. 6, the release of both lugs 13 taking place simultaneously and substantially at the same moment as the release of the lugs 24 of the side braces, so that the harness will open out and can slip off the wearer's body as soon as the knob 26 is operated.

5

When reconnecting the harness, the several lugs may be re-engaged with the locking studs of the central control box and leg-release devices in any order, one at a time or in pairs, and the knob 26 then rotated to lock the engagement.

10

The improved harness may evidently be modified to provide for direct locking and release of the ends of the leg loops 17 by providing them with lugs similar to the lugs 13 connected to the leg strap or seat loop 14; in this modification, each of the leg-release devices 12 will include two locking studs such as 43 for engaging the respective lugs, both studs being carried by the same cover plate 36, and the wire 31 attached to shoe 47 may be tensioned by a single spring disposed centrally between the two studs 43.

20

What I claim is:

1. Parachute harness for aviators, comprising two parachute connections for carrying the entire load, a seat for the aviator, a leg loop secured to said seat and adapted to be carried up between the aviator's legs when seated, two connectors attached to the respective ends of said seat, means for locking said connectors individually to said connections, said leg loop being engageable with said connectors under control of said locking means, said connections, leg loop and locking means being located in front of the aviator in the position of wear, and a single member for simultaneous release of said locking means.

30

2. Parachute harness for aviators, comprising two parachute connections for carrying the entire load, a seat for the aviator, means for locking said connections individually to the respective ends of said seat, said connections and locking means being located in front of the aviator in the position of wear, and means for fastening said connections together above the respective locking means, said fastening means including a control member for simultaneous release of said fastening and locking means.

40

3. Parachute harness for aviators, comprising two parachute connections for carrying the entire load, a seat for the aviator, means for locking said connections to the respective ends of said seat, said connections and locking means being located in front of the aviator in the position of wear, lateral attachments upon said connections, disconnectible means for fastening said attachments together, a control member for locking and releasing said fastening means, and operative connections between said fastening and locking means whereby the release of said fastening means causes release of said locking means.

50

4. Parachute harness for aviators, comprising two lift webs adapted for attachment to a parachute, a seat for the aviator, connectors attached to the respective ends of said seat, disconnectible means for locking said connectors to said lift webs, said lift webs and locking means being located in front of the aviator in the position of wear and being arranged to carry his entire weight when occupying said seat, side members upon said lift webs, disconnectible means for fastening said side members together, a control member for locking and releasing said fastening means, and operative connections between said fastening and locking means whereby the release of said fastening means causes disconnection of

60

5. Parachute harness for aviators, comprising two lift webs adapted for attachment to a parachute, a seat for the aviator, connectors attached to the respective ends of said seat, disconnectible means for locking said connectors to said lift webs, said lift webs and locking means being located in front of the aviator in the position of wear and being arranged to carry his entire weight when occupying said seat, side members upon said lift webs, disconnectible means for fastening said side members together, a control member for locking and releasing said fastening means, and operative connections between said fastening and locking means whereby the release of said fastening means causes disconnection of

70

6. the release of both lugs 13 taking place simultaneously and substantially at the same moment as the release of the lugs 24 of the side braces, so that the harness will open out and can slip off the wearer's body as soon as the knob 26 is operated.

5. Parachute harness for aviators, comprising two lift webs adapted for attachment to a parachute, a seat for the aviator, connectors attached to the respective ends of said seat, disconnectible means for locking said connectors individually to the respective lift webs, a leg loop secured to said seat and adapted to be carried up between the aviator's legs when seated, said leg loop being engageable with said connectors under control of said locking means, said lift webs, leg loop and locking means being located in front of the aviator in the position of wear, said lift webs and locking means carrying the entire weight of the aviator when occupying said seat, and a single control member for simultaneous disconnection of said locking means and disengagement of said leg loop.

6. Parachute harness for aviators, comprising two lift webs adapted for attachment to a parachute, a seat for the aviator, connectors attached to the respective ends of said seat, disconnectible means for locking said connectors to said lift webs, a leg loop secured to said seat and adapted to be carried up between the aviator's legs when seated, said leg loop being engageable with said connectors under control of said locking means, side braces upon said lift webs, disconnectible means for fastening said side braces together, said lift webs, leg loop, side braces, locking means and fastening means being located in front of the aviator in the position of wear, said lift webs and locking means carrying the entire weight of the aviator when occupying said seat, a control member for locking and releasing said fastening means, and operative connections between said fastening and locking means whereby the release of said fastening means causes simultaneous disconnection of said locking means and disengagement of said leg loop.

7. Parachute harness for aviators, comprising two parachute connections for carrying the entire load, a seat for the aviator, means for locking said connections to the respective ends of said seat, said connections and locking means being located in front of the aviator in the position of wear, lateral attachments upon said connections, disconnectible means for fastening said attachments together, a control member for locking and releasing said fastening means, and operative connections between said fastening and locking means, said operative connections including flex-

ible casings, wires slideable within said casings, and springs tensioning said wires, the release of said fastening means freeing the adjacent ends of said wires for sliding movement under spring tension to release said locking means.

8. In parachute harness of the character described, a locking device comprising a body adapted for attachment to a lift web, said body having a slotted wall, a lug connected to one end of the aviator's seat, a cover plate pivotally mounted on said body, a locking stud slideable within said cover plate, a spring controlling the sliding movement of said stud, means for retaining said cover plate in a position wherein said stud intersects the slot in the wall of said body, the insertion of said lug through said slot bringing it into engagement with said stud, and means for displacing said retaining means by manipulation of a control member external to said body.

9. In parachute harness of the character described, a controlling device comprising a body having two opposite slots, a pair of lugs adapted for independent insertion in said slots, locking studs guided in said body and adapted to engage said lugs when inserted in said slots, means for locking said studs in engagement with said lugs and for releasing said studs simultaneously from said lugs, and flexible links tensioned by movement of said lugs into said slots, said flexible links governing the release of other parts of said harness.

10. A parachute harness for an aviator, including front lift webs carrying the entire load, a leg strap in which the aviator sits slingwise, two separate quick-release devices for individually locking said webs to the respective extremities of said leg strap, said quick-release devices being adapted for simultaneous release, and a single controlling means for effecting said simultaneous release.

JOHN RAYMOND CUTHBERT QUILTER.
